(57) **CLAIM**

The ornamental design for a tool handle, as shown and described.

DESCRIPTION

FIG. 1 is a left side plan view of the tool handle of this invention, the right side plan view is a mirror image.

FIG. 2 is a front plan view of the tool handle design of FIG. 1.

FIG. 3 is a rear plan view of the tool handle design of FIG. 1.

FIG. 4 is a top plan view of the tool handle design of FIG. 1; and,

FIG. 5 is a bottom view of the tool handle design of FIG. 1. The dashed lines depicting a tool shank form no part of the design of this invention.
